UNITED STATES PATENT OFFICE.

PAUL J. SIMMEN, OF INDIANAPOLIS, INDIANA.

SYSTEM OF VEHICLE CONTROL.

1,203,146.

Specification of Letters Patent.

Patented Oct. 31, 1916.

Application filed September 24, 1913. Serial No. 791,451.

To all whom it may concern:

Be it known that I, PAUL J. SIMMEN, a citizen of the United States, residing at Indianapolis, in the county of Marion and 5 State of Indiana, have invented certain new and useful Improvements in Systems of Vehicle Control, of which the following is a specification.

This invention relates to train despatching and signaling systems. Its object is a 10 system whereby a despatcher may signal to the trains under his control, and a clear signal for one train will produce a different signal, such as a danger signal, if received 15 by another train; to advise the despatcher, and preferably make a permanent record, of the movements of the train in response to such signals; and to interlock the controlling means at the despatcher's office to avoid 20 accidents.

The accompanying drawings illustrate the invention in diagrammatic form for the sake of clearness.

In said drawings: Figure 1 is a diagrammatic view illustrating a section of the track and the mechanism at the despatcher's office. Fig. 2 is a diagrammatic view of the mechanism on the vehicle. Fig. 3 is a detail sectional view taken on the line 3—3 of Fig. 1.

25 The railway system comprises a single track 5, carrying traffic in both directions, and assumed to run east and west. Along this track are a number of stations A, B, C, D, E, F, which may be actual stations or 30 other convenient dividing points, station A being a terminal station. At each station there is a siding indicated at 6 and two signal rails for each direction of movement, one a home rail 7 nearest the station and 35 the second a distant rail 8 farther away. The two signal rails for each direction are on the same side of the track, and in practice are usually about a third of a mile apart.

40 The four signal rails at each station are connected in common to a conductor 9 leading through a relay coil 10 to a triple throw switch 11 at the despatcher's office, there being one such switch for each station. For 45 clearness in the diagram these switches are shown in position directly above their corresponding stations. Each switch 11 has a neutral position and two extreme positions, in the latter engaging contact members 12 and 13 respectively. All the contacts 12 are

50 connected to a conductor 14, and all the contacts 13 to a conductor 15, which conductors lead, conveniently through switches 16 and 17, to opposite terminals of two batteries 18 and 19, the other terminals of which are grounded. When any switch 11 engages the contacts 12 or 13, it energizes 55 the signal rail 7 or 8 of the corresponding station either negatively or positively with respect to the track; while when it is in 60 neutral position such signal rails are de-energized.

55 Each switch 11 is mounted on a pivot 20 and is provided with an interlocking device 21 secured thereto or made integral 65 therewith and conveniently made in the form of a plate bounded by a convex arc 22 and two concave arcs 23, and these devices of the various switches interlock, as indicated by the switches for stations B, C, and 70 D in the diagram, to prevent any one switch from being operated to produce negative or positive energization of the signal rails of the corresponding station when the switch for the next station to it on either side is in 75 position to produce positive or negative energization of its associated signal rails. For example the switch 11 for station C cannot be moved to engage the contact 12 when the switch for station D engages contact 13, or to engage contact 13 when the switch for station B engages contact 12.

80 In the drawing, 24 indicates an east bound train and 25 a west bound train. Each train, which may consist of a single car, is provided with the equipment shown in Fig. 2 85 of the drawing. A shoe 26 is hingedly mounted at a convenient place on the car and is adapted to engage the successive signal rails 7 and 8 as it moves along the track, 90 during such engagement pressing against a spring 27 and when out of such engagement pressed by the spring against a contact arm 28. One end of the winding of an electromagnet 29 is connected by a conduit 30 to 100 the shoe 26, and the other end is grounded by a conduit 31 connected to the car axle 32 between the wheels 33. The electromagnet has a non-polarized armature 34 and a polarized armature 35. The former engages contacts 36 and 37 when the magnet 29 is energized in either direction, but drops into engagement with a contact 38 when the magnet is deenergized. The polarized armature 35 is moved into its two positions when the 105 110

magnet 29 is energized in opposite directions, remaining in either position in which it happens to be when the magnet becomes deenergized. The polarized armature 35 carries contact members 39 and 40, which engage contacts 41 and 42 respectively when it is in one position and contacts 43 and 44 when it is in the other position. The contacts 41 and 43 are connected together and to one terminal of a clear signal lamp 45, conventionally colored green, and the contacts 38, 43, and 42 are connected together and to one terminal of a danger signal lamp 46, conventionally colored red. The other terminals of the lamps 45 and 46 are connected to the conductor 31. The contact members 39 and 40 are connected respectively to contacts 47 and 48, with either of which a switch arm 49 may be moved into engagement, this switch arm being connected by a wire 50 to the contact 36. The contact 37 is connected by a conductor 51 to the arm 28 and such conductor includes the coil of an electromagnet 52 having an armature 53 which is drawn away from the magnet by a spring 54 to tap a bell 55 when the magnet becomes deenergized. The non-polarized armature 34 and the wire 31 are connected through a reversing switch 56 to the two sides of a local battery 57 carried on the car, the switches 49 and 56 being operated together by a common handle indicated at 58. The signal lamps are conveniently arranged within the usual range of vision of the train operator.

Mechanism is provided for making a record at the despatcher's office of the movement of the trains as follows: Each relay coil 10 when energized closes a switch 59, to complete a circuit extending from one side of a battery 60 through a conductor 61 having branches 62 to each switch, the switch 59, a conductor 63, a solenoid 64 surrounding a perforating plunger 65, and a conductor 66 to the other side of the battery 60. The solenoids 64 and the perforating plunger are conveniently arranged at the despatcher's office in proximity to the interlocking switch system. In front of the needle 67 there is placed a record sheet 68 adapted to be moved in a downward direction over a roller 69 and wound upon another roller 70 by means of a pawl 69 and ratchet 70 operated by an electromagnet 71 energized from the battery 60 and controlled by a clock switch of usual form indicated at 72. The record sheet is ruled with parallel lines 73, transverse to its direction of movement and these lines represent the hour and minute at which such lines pass the operating zone of the series of needles. At the edge of the sheet the time appropriate to each line is preferably written or printed as indicated at 74. The record sheet is also ruled with other parallel lines A, B, C, D, E, F, etc., at right

angles to the lines 73 and so spaced apart as to denote the relative positions of the stations along the road, there being one perforating needle for each station. It will be understood that when a solenoid 64 is energized its needle 65 is propelled forward to puncture the record sheet and is then immediately withdrawn.

The operation of the system is as follows: Assume that the train 24 is to start from the station A and proceed eastward, passing the train 25 coming westward. The despatcher will set the switches 11 for stations A and B, say, to the right and those for stations D, E, and F, say, to the left, as indicated. This locks the switch 11 for station C, so that it can not be moved in either direction because its concave arcs 23, 23 are engaged by the convex arcs 22 of the switch on each side of it. On the train 24, its contact shoe 26 being on the signal rail and the switches 49 and 56 being in the position indicated the movement of the switch 11 for station A closes a circuit from the positive side of the battery 18 through the earth and the grounded track rails 5, 5, the axle 32 of the train, the winding of the electro-magnet 29, the wire 30, the shoe 26, the signal rail 7 or 8, as the case may be, the wire 9 for station A, the relay coil 10, the switch 11, the contact 12, the conductor 14, and the switch 16 to the negative side of the battery 18. This current energizes the magnet 29 and the coil 10, and moves the armatures 34 and 35 into the positions shown, if they are not already in such position. When in such positions these armatures complete a circuit from the positive side of the battery 57 through one arm of the reversing switch 56, the wire 31, the green lamp 45, the contact 41, the finger 39, the contact 47, the switch arm 49, the wire 50, the contact 36, the armature 34, and the other arm of the reversing switch 56 to the negative side of the battery 57, thus giving a clear signal to the operator. The energization of the relay coil 10 also closes the switch 59, thus causing the energization of the solenoid 64 for station A, by the circuit already traced, and operates its perforating plunger 65 to make a mark in the record sheet 68 on the longitudinal line for station A at the proper point to indicate the exact time the clear signal has been received by the train at that station. These circuits remain undisturbed while the contact shoe of the train is in engagement with the signal rail at that station, the train despatcher is advised of the reception of the clear signal by such train and a permanent record is made on the record sheet by the plunger 65. The despatcher is also advised how long the car remains with its contact shoe in engagement with such signal rail because during that time the plunger 65 remains in an elevated

position. As the train 24 passes from the signal rail at station A the shoe 26 passes out of engagement with the rail and engages the arm 28, thus breaking the circuit from the battery 18 to the magnet 29, but completing a holding circuit through the magnet from the positive side of the battery 57 through the switch 56, the wire 31, the winding of the magnet 29, the wire 30, the shoe 26, the arm 28, the wire 51, the contact 37, the armature 34, and the other arm of the reversing switch 56 to the negative side of the battery 57. This holds the armatures 34 and 35 in the same position, thus keeping the green lamp 45 burning. As each signal rail is reached by a car, its shoe 26 engages the rail and is pushed out of engagement with the arm 28, thus breaking the holding circuit for the magnet 29 and deenergizing the magnet 52 to cause the bell 55 to ring. This calls the operator's attention to the fact that there may be a change in the signals. However, if the signal rail is negatively energized as before, as are the signal rails for the stations A and B with the switches 11 in the position shown, the current from the battery 18 maintains the energization of the magnet 29 in the same direction and holds the armatures 34 and 35 in the positions shown to maintain the green lamp burning. If the signal rail is energized in either direction, its engagement by the shoe 26 energizes the corresponding relay coil 10 and operates its perforating needle to advise the despatcher and make a permanent record of the arrival of the train at that point. The home and distant signal rails are provided so that the operator may be warned when approaching a station, and also to enable the despatcher to signal a train at the home rail by a danger signal even although it has passed the distant rail. As the train 24 passes station B and receives a clear signal it then proceeds on to station C, its passage being recorded by two marks on the line B of the record sheet 67. However, when the shoe 26 of the train 24 engages a signal rail at station C (the signal rail of which is deenergized because the switch 11 at that station is in neutral position), the holding circuit for the magnet 29 is broken and the bell 55 is sounded, but as no current is supplied from the signal rail to the magnet 29, the armature 34 drops away from the contacts 36 and 37 and into engagement with the contact 38, and breaks the circuit for the green lamp 45 and closes the circuit for the red lamp 46. This latter circuit is from the positive side of the battery 57 through one arm of the reversing switch 56, the wire 31, the red lamp 46, the contact 38, the armature 34 in its lower position, and the other arm of the reversing switch 56 to the negative side of the battery 57. On see-

ing the red light, to which his attention is called by the bell 55, the operator should stop his train and take such steps as are necessary for protection; for instance, by running his train upon the siding 6 at the station C to allow the passage of the train 25 approaching in the other direction. As the train 24 passes from the deenergized signal rail, the reengagement of the shoe 26 with the contact finger 28 does not re-establish the holding circuit for the magnet 29, because such circuit is broken by the disengagement of the contact 37 and the armature 34 when the latter is in its lower position, therefore the red lamp continues 80 lit and the danger signal is maintained.

When the train 24 has passed stations A and B, the switches 11 for such stations may be turned to their neutral positions, or even to their left hand positions if desired, thus 85 unlocking the switch 11 for the station C so that it can also be turned to the left if desired. The despatcher will not usually so turn the switch 11 for station C until the train 24 is on the siding 6 of such station, but will then do so to produce a positive energization of the signal rails at such station by a circuit from the positive side of the battery 19, the switch 17, the wire 15, the contact 13, the switch 11, the relay coil 95 10, and the wire 9. In the meantime, the train 25 approaching the station C from the east, passing the stations F, E, and D, has its switches 49 and 59 in the other position from that shown, so that the positive energization of a signal rail produced by having the switch 11 for that station in its left hand position, will produce operation of the green lamp 45 on such train in a manner readily apparent. In this train the circuits are 105 the same as on the train 24, except that the currents flow in the opposite direction and the finger 40 and the contacts 42 and 44 take the place of the finger 39 and the contacts 41 and 43 respectively. When the train 25 reaches the signal rail at station C, it will 110 continue westward if the despatcher has thrown his switch 11 for such station to the left as above described to produce a green signal on such train when its shoe 26 engages a positively energized signal rail at such station. The passage of the train 25 past each signal rail is indicated to the despatcher and recorded on the record sheet by the needle 65 as heretofore described. If 115 the driver of the train 24 for any reason passes out of the siding 6 at the station C before the train 25 has passed, or, at any other time, moves his train so that its shoe 26 engages any signal rail which is positively energized, this will produce a reverse flow of current through the magnet 29, causing the polarized armature 35 to move to its other position, thereby breaking the circuit for the green lamp 45, and completing 120 125 130

4
a circuit for the red lamp 46. This last circuit is the same as that already described for the green lamp 45 save that the red lamp 46 and the contact 43 take the place of the green lamp 45 and the contact 40. At the same time this movement of the train 24 will be recorded, and the despatcher will be advised of it, by the resultant action of the relay coil 10 and the responding perforating 5 plunger 65, so that the despatcher can take such steps as are necessary for protection.

The interlocking segments on the switches 11 at the despatcher's office it will be noted are of such shape and form that two adjacent switches corresponding to and controlling the signal rails at adjacent stations cannot be thrown into such a position that they incline toward each other at the same time. A switch can be thrown to the right 15 if the adjacent switch to the right is either at neutral or thrown to the right. Similarly it can be thrown to the left if the adjacent switch to the left is at neutral or thrown to the left, but it cannot be thrown to the right 20 if the adjacent switch to the right is thrown to the left or thrown to the left if the adjacent switch to the left is thrown to the right. Moreover the reversing switches 49 and 56 25 on each car are so arranged that when they are turned to the right the negative energization of the signal rails with which the shoe 26 of the car is brought in contact will operate a clear signal while if they are thrown to the left the same energization will 30 operate a danger signal. The result of this coöperation between the switches 11, the reversing switches on the train and the action of the polarized and non-polarized armatures on the train is such that a clear 35 signal sent through the signal rails to a car going in one direction will result in a danger signal being given to a car going in the other direction or vice versa, while a de- 40 energization of these same rails will result in a danger signal being given to both cars. 45 Moreover, by the system described the operator on each train is warned by a bell that a change of signals may take place whenever he reaches a signal rail. Therefore, the operation of the system as a whole is such that the operator on the train is always informed by a signal within sight and hearing, whether the conditions in front of him denote danger or safety and whether a change 50 of such conditions is impending and after a signal rail has been passed the signal energized by the manipulation given to such rail is continued until another rail is reached by means of the local battery on the car so that 55 the operator feeling that he is being taken care of from the despatcher's office and that his safety is assured can devote his attention to the manipulation of the controlling devices on the train and does not have to di- 60 vide such attention by looking out of the 65

train to observe signals along the track if they are visible or to listen for them if they are audible. And at the central office where the switches are located the despatcher merely by looking at his line of switches 70 can tell at what stations a clear or danger signal will be given to trains going either way and known by a glance at his record sheet where each train is all of the time and knows that owing to the system of interlocking 75 the switches he can not possibly let two trains going in opposite directions into the same section to cause a collision. So that with this system, the operator on the train and the train despatcher both feel reasonably safe.

What I claim is:

1. In a railway signal and controlling system, comprising a trackway divided into sections and an electrically energizable signal 85 rail at each section, a system of switches controlling the direction of energization of such rails, and means controlled by one of the switches for in turn controlling the direction of energization of the rails of adjacent 90 sections.

2. A railway signal system comprising a railway divided by stations into blocks, a signal rail section at each station, switches causing the energization in either direction 95 of such signal rail section at each station, interlocking means between the switches for the different stations, signals carried by the trains and controlled by said signal rails as they are passed by the trains, the signals on 100 the trains being differently operated when the signal rail sections are energized in one direction from the manner in which they are operated when the signal rails are energized in the other direction, and means for 105 indicating at the place where the switches are located that a signal has been received by a train.

3. In a railway signal and controlling system, comprising a trackway divided into 110 sections and an electrically energizable signal rail at each section, a system of switches controlling the energization of such rails, and interlocking means carried by the switches for controlling the operation of adjacent switches when one of the switches is in a predetermined position, to thereby control the direction of energization of the rails of adjacent sections.

4. A railway signal system comprising a 120 railway divided by stations into blocks, a signal rail section at each station, switches causing the energization in either direction of such signal rail section at each station, interlocking means between the switches for 125 the different stations, signals carried by the trains and controlled by said signal rails as they are passed by the trains, the signals on the trains being respectively operated according as the signal rail sections are ener- 130

gized in one direction or the other, and means for indicating at the place where the switches are located the reception of a signal by a train.

- 5 5. A railway signal system comprising a railway divided by stations into blocks, a signal rail section at each station, switches causing the energization in either direction of such signal rail section at each station, 70
 10 interlocking means between the switches for the different stations, signals carried by the trains and controlled by said signal rails as they are passed by the trains, the signals on the trains being differently operated when 75
 15 the signal rail sections are energized in one direction from the manner in which they are operated when the signal rails are energized in the other direction, and means for recording at the place where the switches are located that a signal has been received by a 80 train.

6. A railway signal system comprising a railway divided by stations into blocks, a signal rail section at each station, switches 85
 25 causing the energization in either direction of such signal rail section at each station, interlocking means between the switches for the different stations, signals carried by the trains and controlled by said signal rails as 90
 30 they are passed by the trains, the signals on the trains being differently operated when the signal rail sections are energized in one direction or the other or deenergized, and means for recording at the place where the switches are located the reception of a signal by a train.

7. A railway signal system comprising a railway divided by stations into blocks, a signal rail section at each station, switches 95
 40 causing the energization in either direction of such signal rail section at each station, interlocking means between the switches for the different stations, signals carried by the trains and controlled by said signal rails as 100
 45 they are passed by the trains, the signals on the trains being differently operated when the signal rail sections are energized in one direction from the manner in which they are operated when the signal rails are energized in the other direction, and means for 105
 50 automatically recording at the place where the switches are located that a signal has been received by a train.

8. A railway signal system comprising a railway divided by stations into blocks, a signal rail section at each station, switches causing the energization in either direction of such signal rail section at each station, 110
 55 interlocking means between the switches for the different stations, signals carried by the trains and controlled by said signal rails as they are passed by the trains, the signals on the trains being differently operated when the signal rail sections are energized in one direction or the other or deenergized, and 115
 60

means for automatically recording at the place where the switches are located the reception of a signal by a train.

9. A railway signal and controlling system comprising a trackway divided into sections, electrically energizable signal rails at each section, a clear signal and a danger signal carried by a car, a device operating the car signals as the car passes the signal rails, through the energization of the latter, 70
 whereby if the signal rails are energized positively a clear signal will be produced on the car and if they are energized negatively a danger signal will be produced on the car, a switch on each car adapted to reverse the operation of such energization to produce signals of directly opposite import from the energization of the signal rails in the same direction, a system of switches for controlling the energization of the signal 75 rails at each section, and means for interlocking adjacent switches in succession in the same direction to prevent one from being turned in the opposite direction, including a device on each switch, said devices interengaging when moved to a predetermined 80 relation and being disengaged when moved to a different relation.

10. A railway signal and controlling system comprising a trackway divided into sections, 95
 electrically energizable signal rails at each section, a clear signal and a danger signal carried by a car, a device operating the car signals as the car passes the signal rails, through the energization of the latter, 100
 whereby if the signal rails are energized positively a clear signal will be produced on the car and if they are energized negatively a danger signal will be produced on the car, a switch on each car adapted to reverse the operation of such energization to produce signals of directly opposite import from the energization of the signal rails in the same direction, a system of switches for controlling the energization of the signal 105 rails at each section, and means for interlocking adjacent switches in succession in the same direction to prevent one from being turned in the opposite direction.

11. A railway signal and controlling system comprising a trackway divided into sections, electrically energizable signal rails at each section, a clear signal and a danger signal carried by a car, a device operating the car signals as the car passes the signal 110 rails, through the energization of the latter, whereby if the signal rails are energized positively a clear signal will be produced on the car and if they are energized negatively a danger signal will be produced on the car, a switch on each car adapted to reverse the operation of such energization to produce signals of directly opposite import from the energization of the signal rails in the same direction, a system of switches for con- 115
 120
 125
 130

- trolling the energization of the signal rails at each section, and means for interlocking adjacent switches in succession in the same direction to prevent one from being turned in the opposite direction, including a device on each switch adapted to engage a similar device on the switches on each side of each switch, when said switches are turned to a predetermined relation.
12. In a system for controlling the movement of railway trains comprising a trackway divided into sections and electrically energizable signal rails at each section, a series of switches one controlling the direction of energization of the rails at each section and means for interlocking the switches against improper actuation.
13. In a system for controlling the movement of railway trains comprising a trackway divided into sections and electrically energizable signal rails at each station, a series of switches one controlling the direction of energization of the rails at each section and means for interlocking the switches whereby when energization of the signal rails of a section is in one direction when the switch of that section is turned in one direction the next switch in series in the same direction cannot be turned in the opposite direction to produce energization in an opposite direction of the rails of its section.
14. In a railway signal system signal rails and a series of switches, adapted to energize corresponding signal rails positively if the switches are turned in one direction, and to energize the rails negatively if they are turned in another direction and means for preventing any switch from being turned in the wrong direction.
15. In a railway signal system signal rails and a series of switches, adapted to energize corresponding signal rails positively if the switches are turned in one direction, and to energize the rails negatively if they are turned in another direction and means for preventing any switch from being turned in the wrong direction, including a device for each switch provided with segmental edges.
16. In a railway signal system signal rails and a series of switches, adapted to energize corresponding signal rails positively if the switches are turned in one direction, and to energize the rails negatively if they are turned in another direction and means for preventing any switch from being turned in the wrong direction, including a device for each switch provided with segmental edges one edge being convex and two being concave.
17. In a railway signal system signal rails and a series of switches, adapted to energize corresponding signal rails positively if the switches are turned in one direction, and to energize the rails negatively if they are turned in another direction and means for preventing any switch from being turned in the wrong direction, including a device for each switch provided with segmental edges one edge being convex and two being concave, the convexity and concavity being defined by arcs of substantially the same radius.
18. In a railway signal system signal rails and a series of switches, adapted to energize corresponding signal rails positively if the switches are turned in one direction, and to energize the rails negatively if they are turned in another direction and means for preventing any switch from being turned in the wrong direction, including a bell shaped device for each switch.
19. In a railway signal system signal rails and a series of switches, adapted to energize corresponding signal rails positively if the switches are turned in one direction, and to energize the rails negatively if they are turned in another direction and means for preventing any switch from being turned in the wrong direction, including a bell shaped device for each switch, having a terminal convex boundary and two lateral concave boundaries.
20. In a railway signal system signal rails and a series of switches, adapted to energize corresponding signal rails positively if the switches are turned in one direction, and to energize the rails negatively if they are turned in another direction and means for preventing any switch from being turned in the wrong direction, including a bell shaped device for each switch, having a terminal convex boundary and two lateral concave boundaries, all of the curvatures being on substantially the same radius.
21. A railway signal and controlling system comprising a trackway divided into sections, electrically energizable, signal rails at each section, a clear signal and a danger signal carried by a car, a device operating the car signals as the car passes the signal rails, through the energization of the latter, whereby if the signal rails are energized positively a clear signal will be produced on the car and if they are energized negatively a danger signal will be produced on the car, a switch for each section adapted to control the direction of energization of its signal rails, and means for interlocking the switches belonging to adjacent sections whereby the switches are prevented from causing the energizing of the signal rails at such sections in opposite directions.
22. In a railway signal and controlling system comprising a trackway divided into sections and electrically energizable signal rails at each section, a system of switches one for each section controlling the direction of energization and deenergization of such rails and means for interlocking them against improper actuation.

23. In a railway signal and controlling system comprising a trackway divided into sections and electrically energizable signal rails at each section, a system of switches one for each section controlling the direction of energization and deenergization of such rails and means for interlocking them against improper actuation, whereby a current in the same direction may be sent to the rails in adjacent sections in the direction of movement of a car, but currents in opposite directions can not be sent to the rails in such sections.
24. In a railway signal and controlling system comprising a trackway divided into sections and electrically energizable signal rails at each section, a system of switches one for each section controlling the direction of energization and deenergization of such rails and means for interlocking them against improper actuation, whereby a current in one direction may be sent to the rails in one section and a current in the same direction sent to the rails in adjacent sections.
25. A railway signal and controlling system comprising a trackway divided into sections, electrically energizable signal rails at each section, a clear signal and a danger signal carried by a car, a device operating the car signals as the car passes the signal rails, through the energization of the latter, whereby if the signal rails are energized positively a clear signal will be produced on the car and if they are energized negatively a danger signal will be produced on the car, a switch on each car adapted to reverse the operation of such energization to produce signals of directly opposite import from the energization of the signal rails in the same direction, and a system of switches for separately controlling the energization of the signal rails at each section and maintaining a plurality of said rails energized simultaneously.
26. A railway signal and controlling system comprising a trackway divided into sections, electrically energizable signal rails at each section, a clear signal and a danger signal carried by a car, a device operating the car signals as the car passes the signal rails, through the energization of the latter, whereby if the signal rails are energized positively a clear signal will be produced on the car and if they are energized negatively a danger signal will be produced on the car, a switch on each car adapted to reverse the operation of such energization to produce signals of directly opposite import from the energization of the signal rails in the same direction, and a system of switches for separately controlling the energization of the signal rails at each section and maintaining a plurality of said rails energized simultaneously, some positively and some negatively.
27. A railway signal and controlling system, comprising a trackway divided into sections, electrically energizable signal rails at each section, a clear signal and a danger signal carried by a car, a device operating the car signals as the car passes the signal rails, through the energization of the latter, whereby if the signal rails are energized positively one signal will be produced on the car, and if they are energized negatively, the other signal will be produced on the car, means on each car for reversing the operation of such energization to produce signals of directly opposite import from the energization of the signal rails in the same direction, and means for controlling the energization of the signal rails.
28. A railroad, signals, signal controlling devices at intervals along the road, car-carried means to control the signals, each device adapted to coöperate with the car-carried means on cars moving only in the direction governed by such device, means at a central station for controlling the said devices and controlling one device to give a clear signal to a car moving in one direction only, and to control a second device to give a clear signal to a car moving in the opposite direction only, and mechanism controlling said central station means to prevent a clear signal being given to a car moving in either direction between the two first mentioned devices.
29. A railroad, signals, signal controlling devices at intervals along the road, car-carried means to control the signals, each device adapted to coöperate with car-carried means on cars moving only in the direction governed by such device, and means at a central station for controlling the said devices and controlling one device to give a clear signal to a car moving in one direction only and to control a second device to give a clear signal to a car moving in the opposite direction only and to give a danger signal to a car moving in either direction between the two first mentioned devices.
30. A railroad, traffic controlling signals therefor, traffic carried signal controlling means, signal controlling devices located along the railroad, coöperating with the traffic carried means and each controlling signals for traffic in one direction only, a central station, a means thereat for each device for controlling it to cause clear or danger signals, the central station means so controlling each other that when a plurality of said means controls a set of devices to cause the giving of a clear signal for traffic moving in one direction only at a plurality of locations, and another plurality of said means controls a non-adjacent set of devices to cause the giving of a clear signal for traffic moving in the opposite direction only at another plurality of locations, the means controlling a device between said sets

will be prevented from causing the giving of a clear signal.

31. A railroad, block stations therefor, and mechanism, including means controlled by cars on the railroad for giving at each block station clear signals to such cars, said mechanism including means for conditioning said mechanism to give a clear signal to a car moving in one direction only at one block station and also to give a clear signal to a car moving only in the opposite direction at a different block station, and said mechanism also including means for preventing the giving of a clear signal at a block station between said block stations.
32. A railroad, block stations therefor, and mechanism including means controlled by cars on the railroad for giving at each

block station clear signals to such cars, said mechanism including means for conditioning said mechanism to give a clear signal to a car moving in one direction only at one block station and also to give a clear signal to a car moving only in the opposite direction at a different block station, said mechanism also including means for locking the conditioning means for a block station between said block stations in a position to give a danger signal at said intermediate block station.
